UNITED STATES PATENT OFFICE

KARL R. TELLEFSEN, OF PHILADELPHIA, PENNSYLVANIA

OUTRIGGER DAVIT FOR SHIPS

Application filed April 6, 1929. Serial No. 353,015.

The present invention relates to an improved outrigger for ships, and especially a construction such as will enable the davit to be operated under all conditions.

5 The davits now in actual use are not of the outrigger type, such as will permit the life boat to be lowered without causing the life boat to fill with water or be smashed against the ship's side. For example the davits now 10 constantly in use simply turn outward to dispose the life boat in a position to be lowered into the water, and such operation can easily be accomplished when the water is calm. However during a rough sea the life boat as 15 it is being lowered subsequently to moving it just beyond the ship's side in a position to be lowered into the water will swing back and forth toward the ship's side, and will generally crash against the side of the ship, 20 and resulting very often in serious injury to the life boat.

Then again when a life boat is eventually lowered into the water after being tossed back and forth toward the ship's side, is very 25 apt to fill with water owing to its extreme tilting. These difficulties render it extremely difficult to properly lower a life boat in a rough sea.

With these facts in view it is the purpose 30 of the present invention to provide an improved outrigger davit, which is capable of lowering the life boat without the above disadvantages, the life boat when being lowered, even though the ship is rolling considerable, 35 may be disposed a substantial distance from the ship's side, preventing it from smashing against the side of the ship, and thereby preventing the life boat from tilting back and forth as it finally reaches and rests in the 40 water.

Another purpose is to provide an outrigger davit which may be operated from the boat deck, until the life boat finally is lowered into the sea.

45 A further purpose is to provide a davit of this character having swivel frames mounted on the davit standards, so that they are capable of rotating, in order to move the arms mounted on the frames from their inward 50 positions to outward positions, so that the

life boat may be disposed a short distance laterally of the ship's side and in a position above the surface of the water, whereby the davit standards may be substantially lowered.

55 A still further purpose is to provide in a davit of this kind means to cause the davit standard to tilt to positions to off-set the list or the roll of the ship, so that the davit standards may be tilted laterally and downwardly.

It is to be understood that the particulars herein given are in no way limitative, and that while still keeping within the scope of the invention, any desired modification of details and proportions may be made in the 65 construction of the appliance according to circumstances.

The invention comprises further features and combination of parts to be hereinafter set forth, shown in the drawings and claimed.

70 In the drawings:

Figure 1 is view of a portion of a ship, showing the improved davit as applied and including a winch for allowing the davit to be swung outwardly and downwardly for the 75 purpose of lowering the life boat.

Figure 2 is a sectional view on line 2-2 of Figure 1.

Figure 3 is a sectional view on line 3-3 of Figure 1.

Figure 4 is a sectional view through a jack, to be mounted on the boat deck as in Figure 1 for operating the davit standards outwardly and downwardly, when it is desired to offset the side list or roll of the ship.

80 Figure 5 is a section of a portion of a ship, showing the improved davit arranged with the davit standards moved to positions laterally and downwardly of the ship's side, whereby the life boat may be eventually lowered into the water.

Figure 6 is a sectional view on line 6-6 of Figure 5.

Figure 7 is a top plan view of a portion of the ship's boat deck showing the davit applied with the life boat laterally and downwardly positioned, showing the cable of each windlass slightly inward to illustrate construction below.

Figure 8 is a detailed sectional view of the

arm 36 and the stud 65 with immediate associated parts.

Referring to the drawings, 1 identifies a portion of a ship, the main deck 2, the mid deck 3 and the boat deck 4 being shown, and on the boat deck a winch or windlass 5 is mounted. This winch comprises a frame 6, wherein a drum 7 is journaled, the frame 6 having the standards 8, between the upper ends of which transverse plates 9 are bolted. There are two winches of the same construction used, one for each davit, standard, and secured to one end of the plate 9 is a guy wire 10, which in turn is connected at 11 to the boat deck. Each winch also is provided with spur gears 12, carried by the shaft 13 of the drum 7. The gears 12 mesh with pinions 14 on a shaft 15. The pinions 14 in turn mesh with pinions 15a on a crank shaft 16. An operator may man the cranks at both ends of the shaft 15 so as to impart movement to the drum, on which a lowering and hoisting cable 17 is wound.

The other end of each plate 9 has a clevis hook connected to a pulley block 19 of a block and tackle. Each pulley block 19 has two pulleys.

Adjacent the projecting part of the mid-deck and riveted to the solid bulwark rising from the mid-deck are angle bearings or plates 20, between the lateral projecting parts of which a davit standard 21 is pivotally bolted at 22.

Normally each davit standard is disposed in an upright position as in Figure 1.

However when it is desired to lower a life boat the davit standard may be moved pivotally outwardly and downwardly, so as to dispose the upper end of the davit standard a substantial distance out from the ship's side.

The outer margin of the boat deck is provided with a gutter 23, to which castings 24 are riveted at 25. The castings or plates, of which there are two, one for each davit standard, have lateral ears 26, a pair at each end. Furthermore the central portion of each plate or casting 24 has a crotch bearing 27, into which the davit standard 21 fits when in an upright position, to relieve lateral strain on the standard. Pivoted between one pair of ears 26 is a hasp 27a, which overlies the davit standard, and the one pair of ears receive an eye-pin 28, behind which the curved end of the hasp 27a engages. When it is desired to allow the davit to move outwardly and downwardly the eye-pin 28 may be removed to allow the hasp to swing open, which will permit outward movement of the davit, to assume the position as in Figure 5.

Each davit standard has a shoulder 29, which supports a frame 30 swivelly. This frame 30 comprises opposed side T-irons 31, between which bearings 32 are riveted at 33. These bearings are of the construction shown in Figure 3, thereby permitting the frame 30

to swivel on the standard 21 and in doing so be supported on the shoulder 29. A washer 34 engages against one of the bearings 32, with a cotter pin or similar member 35 engaging through the end of the standard 21 to retain the frame 30 adjacent the shoulder.

An arm 36 though it is of the shape shown in Figure 5 may be of any other suitable formation is riveted or otherwise secured at 37 and 38 to the ends of the T-irons 31.

One end of this arm 36 has an extension plate 39, to which an eye of a pulley or sheave block 40 is attached. This block 40 carries two pulleys, same as the block 19. The cable 17 passes from the drum 7 and upwardly over one of the pulleys in the block 19, and then down toward the block 40 and over one of the pulleys in the latter block, and then upwardly over a second pulley in the block 19 and then again downwardly over the second pulley of the block 40, and passes upwardly in the direction of and attached to the block 19 as at 41. In this way by operating the drum 7 the davit standard can be moved to a perpendicular position arising from the mid-deck of the ship. By allowing the cable to pay out or unwind from the drum 7, provided there is no list or rolling to the ship and after releasing the hasp, the davit standard can swing outwardly and downwardly as in Figure 5.

As shown in Figures 1 and 4 a jack 42 is provided. This jack comprises a casting 43 having a base and two bearings. The two bearings as identified by the numeral 44, are for the screw 45. The screw is not threaded in the bearings but movable longitudinally therethrough and without rotating and to accomplish this result the screw is provided with a longitudinal groove 46 into which a key 47 engages. The key and the groove prevent rotation of the screw but allows the screw to move longitudinally on the bearings.

Threaded on the screw, however, is a wheel 48, which may be operated by hand if so desired, but preferably operated by a handle 49. This handle engages any one of the sockets 50 in the periphery of the wheel, and since the wheel is incapable of movement longitudinally of the screw, the screw is moved threadingly through the wheel, when the wheel is rotated. One end of the screw is provided with a fork 51, which straddles the davit standard. By inserting the handle 49 in first one and then another of the sockets of the wheel the screw may be fed longitudinally through the casting and since the fork straddles the davit standard, the standard may be urged outwardly. This operation is essential and is accomplished when the ship is listing or rolling, and especially when the ship lists in a direction toward the ship's body, as shown in dotted lines in Figure 5. This jack is not a stationary fixture on the boat deck. However when the ship is rolling or listing,

the jack may be carried to the davit and then positioned so that the base 53 of the casting 43 may be disposed in a depression 54 of the boat deck. When so disposed the screw may be operated to move the davit standard outwardly.

It is obvious that since there are two davits employed for the purpose of out-rigging a life boat, so that it may be lowered to the surface of the water without crashing against the ship's side or so rolling as to fill with water, there are two jacks, one for each davit standard, and there are two winches, one for each davit standard.

As shown in Figures 1 and 5 a cable 56 is attached at 57 to an eye of a pulley block 58. Another eye 59 of the pulley block 58 is engaged with the plate 55. The pulley block 58 has three pulleys, as shown in Figure 5, and the cable 56 passes from its attachment at 57 of the block 58 downwardly over one of the three pulleys of a pulley block 60, and then upwardly over one of the pulleys of the block 58 and then downwardly over the intermediate pulley of the block 60 and then upwardly over the intermediate pulley of the block 58, and again downwardly over the third pulley of the block 60 and upwardly over the third pulley of the block 58, and then over a single pulley of a block 61. This cable then extends in a direction toward the ship and is anchored on what is known as a cleat 62. By paying out this cable 56 from the cleat 62, that is after the davit standard has been allowed to move outwardly and downwardly as in Figure 5 the gravity of the life boat will allow the boat to lower into the surface of the water.

As illustrated in the top plan view in Figure 7 the arms 36 at the upper ends the two davit standards are connected by means of a span wire or cable 64. To connect the span wire a stud 65 is riveted on each of the arms 36 as shown more clearly in Figure 8. The rivets 66 pass through the base of the stud 65 and through the flanges of the arm 36, and swiveled on the stud is a plate 67. The span wire 64 connects the adjacent ends of the two plates 67, while connected to the remote ends of the plates 67 are guy wires 68. These guy wires 68 extend in inclined directions down toward a portion not shown of the edge of the boat deck, and are designed to be swivelly connected to such edge portion in order to reinforce the davit standards, and to hold the span wire taut and thereby prevent any tension such as would cause the davit standards to be forced toward each other.

Mounted on the davit standards are clamping collars 69, between the ends 70 of which braces 71 are secured. These braces are in turn bolted at 72 to angle plates 73, which are riveted to the solid bulwark 74, which rises from the mid-deck. By means of these braces 71 the davit standards are additionally reinforced against movement toward each other.

In operating this davit apparatus, the life boat normally resting on its beds 75 which have recesses 76, the swiveled frames 30 are moved, so that one end of the life boat may first move outwardly in a direction between the davit standards, one of the winches allowing one of the cables 17 to pay out, and the same end of the life boat further moved until the opposite end of the life boat moves outwardly in a direction between the davit standards, until the life boat assumes a position a short distance outwardly of and slightly above the boat deck as in full lines in Figure 1. Then by permitting both cables 17 to pay out or unwind from both winches, the gravity of the life boat causes the davit standards to tilt outwardly and downwardly as in full lines in Figure 5. After the life boat has been so disposed an operator may pay out the cable 56 from the cleat 62, until the life boat lowers into the surface of the water.

As previously stated should the ship be rolling or listing, the jacks may be used in the manner previously set forth.

The invention having been set forth, what is claimed is:

1. In a davit apparatus, the combination with a pair of davit standards operatively mounted on a ship's side adjacent the ship's mid-deck, and having an interconnecting brace and lateral inclined remote braces, of frames operatively swiveled on the upper ends of the standards and provided with laterally disposed arms, block and tackle means connected to certain corresponding ends of said arms including cables, certain other corresponding opposite ends of the arms having block and tackle connections including cables for the suspension of a life boat between the two davit standards, cleats on the ship's boat deck for holding the second cables fast, the unwinding of the second cables allowing the life boat to lower, and means operatively associated with the first cables for paying them out and rewinding them, for allowing the standards to move outwardly and downwardly and then dispose them in upright position and means on the boat deck for imparting an initial outward movement of the standards when the ship is listing.

2. In a davit apparatus, the combination with a pair of davit standards operatively mounted on a ship's side adjacent the ship's mid-deck, and having an interconnecting brace and lateral inclined remote braces, of frames operatively swiveled on the upper ends of the standards and provided with laterally disposed arms, block and tackle means connected to certain corresponding ends of said arms including cables, certain other corresponding opposite ends of the arms having block and tackle connections including cables for the suspension of a life boat between the two davit standards, cleats on the ship's boat

- deck for holding the second cables fast, the unwinding of the second cables allowing the life boat to lower, and means operatively associated with the first cables for paying them out and rewinding them, for allowing the standard to move outwardly and downwardly and then dispose them in upright positions, and means mounted on the edge of the boat deck for retaining the standards in upright positions and relieving strains on said bracing means.
3. In a davit apparatus, the combination with a pair of davit standards operatively mounted on the ship's side adjacent the ship's mid-deck, of frames operatively swiveled on the upper ends of the standards and provided with laterally disposed arms, block and tackle means connected to certain corresponding ends of said arms including cables, certain other corresponding opposite ends of the arms having block and tackle connections including cables for the suspension of a life boat between the two davit standards, cleats on the ship's boat deck for holding the second cables fast, the unwinding of the second cables allowing the life boat to lower, and means operatively associated with the first cables for paying them out and rewinding them, for allowing the standard to move outwardly and downwardly and then dispose them in upright positions, angle braces between the davit standards and connecting the ship's side and mid-portions of the standards to reinforce them against movement toward each other.
4. In a davit apparatus, the combination with a pair of davit standards operatively mounted on a ship's side adjacent the ship's mid-deck, of frames operatively swiveled on the upper ends of the standards and provided with laterally disposed arms, said frames comprising T-irons and transverse bearings with lateral flanges operatively secured to the flanges of the T-irons, block and tackle means connected to certain corresponding ends of said arms including cables, certain other corresponding opposite ends of the arms having block and tackle connections including cables for the suspension of a life boat between the two davit standards, cleats on the ship's boat deck for holding the second cables fast, the unwinding of the second cables allowing the life boat to lower, and means operatively associated with the first cables for paying them out and rewinding them, for allowing the standard to move outwardly and downwardly and then dispose them in upright positions, a span wire with its opposite ends operatively swiveled between the arms, and guy wires extending from the swiveled connections of the span wire and connecting with the ship's side at remote distances from the mountings of the standards and in alignment with the mountings.
5. In a davit apparatus, the combination with a pair of davit standards operatively mounted on a ship's side adjacent the ship's mid-deck, of frames operatively swiveled on the upper ends of the standards and provided with laterally disposed arms, said frames

comprising T-irons and transverse bearings with lateral flanges operatively secured to the flanges of the T-irons, block and tackle means connected to certain corresponding ends of said arms including cables, certain other corresponding opposite ends of the arms having block and tackle connections including cables for the suspension of a life boat between the two davit standards, cleats on the ship's boat deck for holding the second cables fast, the unwinding of the second cables allowing the life boat to lower, and means operatively associated with the first cables for paying them out and rewinding them, for allowing the standard to move outwardly and downwardly and then dispose them in upright positions, angle braces between the davit standards and connecting the ship's side and mid-portions of the standards to reinforce them against movement toward each other.

6. In a davit apparatus, the combination with a pair of davit standards operatively mounted on a ship's side adjacent the ship's mid-deck, of frames operatively swiveled on the upper ends of the standards and provided with laterally disposed arms, said frames comprising T-irons and transverse bearings with lateral flanges operatively secured to the flanges of the T-irons, block and tackle means connected to certain corresponding ends of said arms including cables, certain other corresponding opposite ends of the arms having block and tackle connections including cables for the suspension of a life boat between the two davit standards, cleats on the ship's boat deck for holding the second cables fast, the unwinding of the second cables allowing the life boat to lower, and means operatively associated with the first cables for paying them out and rewinding them, for allowing the standard to move outwardly and downwardly and then dispose them in upright positions, a span wire with its opposite ends operatively swiveled between the arms, and guy wires extending from the swiveled connections of the span wire and connecting with the ship's side at remote distances from the mountings of the standards and in alignment with the mountings.

In testimony whereof, he affixes his signature.

KARL R. TELLEFSEN.
